United States Patent Office

Des. 175,460
Patented Aug. 30, 1955

175,460

HANDBAG OR SIMILAR ARTICLE

Herbert S. Chase, Flushing, N. Y., assignor to Bernard Cahn Co., Inc., New York, N. Y.

Application February 15, 1955, Serial No. 34,525

Term of patent 3½ years

(Cl. D87—3)

I claim:

The ornamental design for a handbag or similar article, substantially as shown and described.
